FURNACE DOOR.

APPLICATION FILED NOV. 21, 1906.

2 SHEETS—SHEET 2.

UNITED STATES PATENT OFFICE.

HAZE HAMILTON MAGWIRE, OF MONTPELIER, IDAHO.

FURNACE-DOOR.

No. 876,819.

Specification of Letters Patent.

Patented Jan. 14, 1908.

Application filed November 21, 1906. Serial No. 344,523.

To all whom it may concern:

Be it known that I, HAZE HAMILTON MAGWIRE, a citizen of the United States, residing at Montpelier, in the county of Bear Lake and State of Idaho, have invented certain new and useful Improvements in Furnace-Doors, of which the following is a specification.

This invention relates to new and useful improvements in furnace doors and it pertains particularly to a door for locomotive furnaces.

The invention aims as a primary object to provide a door embodying means for insuring a more perfect combustion of fuel and a consequent reduction in the amount of smoke and in the amount of fuel consumed. This object is attained by the provision of novel air admission and deflecting means whereby the draft shall be induced directly over the fire box to permit of the air acting upon the furnace gases to reduce the unconsumed carbon particles therein.

The invention aims as a further object to provide novel means for regulating the amount of air admitted through the door into the furnace.

The detailed construction will appear in the course of the following description, in which reference is made to the accompanying drawings forming a part of this specification, like characters of reference designating similar parts throughout the several views wherein:

Figure 1 is a front elevation of a furnace door constructed in accordance with my invention. Fig. 2 is a side elevation of the same looking towards the hinges located at one side thereof. Fig. 3 is a horizontal section on the line 3-3 of Fig. 1. Fig. 4 is a fragmentary rear elevation showing the deflecting hood. Fig. 5 is a view illustrating in front plan and perspective the respective members of the lower hinge joint, to be hereinafter specifically referred to, and Fig. 6 is a fragmentary front elevation of a slightly modified form of air or draft regulating device.

The invention specifically embodies a substantially oval open frame 1 which is secured to the fuel opening of the furnace and to which the door 2 is hinged. To this end the frame 1 is provided with spaced ears 3 having aligned apertures therein to receive the pintle 4. The ears 3 serve as stationary hinge members to support the door 2, the lat-

ter being provided on one side thereof with spaced ears 5 which rest upon the adjacent ears 3 and through which the pintle 4 is inserted. For the purpose of preventing accidental movement of the door in its closed or open position by reason of the motion of the engine or for other well known causes the lower ear 5 is provided with angularly disposed ribs 6, illustrated in Fig. 5 which engage in correspondingly arranged V-shaped grooves 7 in the adjacent ear 3. The ribs 6 engage in the grooves 7 with sufficient accidental movement of the door 2, but ride over the sides of said grooves as cams when the door is swung in either direction by the operator.

The door 2 is formed with openings 8 there-in between which is a vertical post 9. Adjacent the outer side edges of the openings 8 are vertical overhanging flanges 10 which serve as guides for a plate 11 slidable therebetween. The plate 11 serves as a vertical draft regulator and is formed with a central vertical slot 12. The post 9 has a horizontal stud 13 which projects loosely through the slot 12 and is threaded to receive a wing nut 14. The wing nut 14 serves to hold the plate 11 in any position to which it may be moved by engaging the sides of said plate frictionally in the well known manner. The lower portion of the plate 11 is extended centrally and downwardly to afford a finger piece 15 by means of which said plate may be raised or lowered according to the adjustment desired.

Means are provided for positively locking the door in its closed position. To this end the frame 1 is provided on the side opposite the above described hinge joint with a catch 16 having an upwardly inclined front face. The door 2 is provided with a resilient latch member 17 rigidly secured at its rear end between lugs 18 and having its free end enlarged as at 19 to afford a handle. The handle 19 has a portion thereof shaped to engage the catch 16 when the door is closed and to prevent the same from being opened except by lifting the latch member 17. The play of the latch member 17 is limited by spaced lugs 20 which are bridged by a vertical strap 21 secured thereto at its ends.

Referring to Figs. 3 and 4, I have illustrated a deflecting hood 22 having an inclined rear wall 23 and straight and parallel sides 24. The latter are formed along their front edges with beads 25 which are positively engaged in conformable overhanging flanges 26 hav-

ing a slightly downward convergent disposition. This disposition of flanges 26, provides wide shoulders at the top ends of the flanges, which shoulders are shown as sloping downwardly. As shown in Fig. 2, the sides 24, of hood 22, are provided with upward extensions which are shaped to seat on said shoulders of flanges 26, thus preventing downward movement of the hood.

10 The modified embodiment shown in Fig. 6 resides in the construction of the plate 11 and its associated parts. In Fig. 6 the two openings 8 and the post 9 are dispensed with and a single enlarged opening is employed. This 15 enlarged opening is not shown since it is enclosed by the plate 11, which in its body portion is imperforate, said plate being provided with a central upward extension 27 having a vertical groove 28 therein. The door 2 is 20 provided with a threaded stud 29 which projects through the groove 28 and receives an adjusting wing nut 30. The upper end of the extension 27 is bent to form a finger piece 31 for raising and lowering said plate as will be 25 readily apparent.

In practical use the plate 11 is adjustably positioned with respect to the openings 8 to increase or decrease the size of the same in correspondingly regulating the draft there- 30 through into the furnace. The air induced through the openings 8 is kept from dissipation by the hood 22 and impinges against the inclined rear wall 23 of said hood by which it is deflected downwardly in a well defined cur- 35 rent over the fire where it commingles with the furnace gases.

Having fully described my invention, I claim:

1. A door for furnaces having an opening 40 formed therein and provided adjacent the sides of said opening with vertical overhang- ing flanges, a plate slidably held between said flanges and having a portion of its material formed with a vertical slotted opening, said

door being formed with a horizontal threaded 45 stud projecting through said slotted opening and a wing nut carried upon said stud and de- signed to bear frictionally against said plate.

2. A door for furnaces having an opening 50 formed therein and provided on its rear face adjacent to the sides of said opening with vertical overhanging flanges arranged in down- wardly converging relation and a hood em- bodying straight sides having beaded front edges engaged with said flanges and an in- clined rear portion.

3. A door for furnaces having an opening 55 formed therein, vertical overhanging flanges having a downwardly convergent disposition 60 on the rear face of said door adjacent to the sides of said opening, a shoulder formed on the top end of each flange, a hood having sides, and an inclined rear portion, beads on the front ends of said sides engaged with said flanges, and upward extensions formed on 65 the tops of said hood sides to project over the said shoulders of said flanges and seat there- on to hold the hood against downward move- ment.

4. A door for furnaces having an opening 70 formed therein, a post extending vertically across said opening at the center of the latter, vertical overhanging flanges projecting from the front face of said door adjacent the sides 75 of said opening, a plate slidably held between said flanges and engaging the front face of said post, said plate being formed with a ver- tical slot which aligns with said post and is closed at its rear thereby, a stud projecting from said post through said slot, and a nut on 80 said post bearing against said plate.

In testimony whereof I affix my signature, in presence of two witnesses.

HAZE HAMILTON MAGWIRE.
